HIGH SPEED ATTACHMENT FOR FOOD CUTTER

Melvin E. Bricker, 2723 Saddleback Drive,
Cincinnati, Ohio 45244

Filed Apr. 24, 1968, Ser. No. 11,602

Term of patent 14 years

Int. Cl. D15—12

U.S. Cl. D55—1

FIG. 2

FIG. 1

FIG. 3

FIG. 5

FIG. 4

FIG. 6

FIG. 1 is a front elevational view of the high speed attachment for food cutter of the present invention;

FIG. 2 is a right elevational view of the high speed attachment for food cutter of the present invention;

FIG. 3 is a left elevational view of the high speed attachment for food cutter of the present invention;

FIG. 4 is a rear elevational view of the high speed attachment for food cutter of the present invention;

FIG. 5 is a top elevational view of the high speed attachment for food cutter of the present invention; and

FIG. 6 is a bottom elevational view of the high speed attachment for the food cutter of the present invention.

I claim:

The ornamental design for a high speed attachment for food cutter, as shown.
